UNITED STATES PATENT OFFICE

138,750

DESIGN FOR A COMBINATION TOOL

Oscar L. Swenson, Toledo, Ohio, assignor of forty-nine per cent to Ben J. Cheeseman,
Toledo, Ohio

Application May 24, 1944, Serial No. 113,746

Term of patent 3½ years

(Cl. D54—13)

To all whom it may concern:

Be it known that I, Oscar L. Swenson, a citizen of the United States and resident of Toledo, in the county of Lucas and State of Ohio, have invented a new, original, and ornamental Design for a Combination Tool, of which the following is a specification, reference being had to the accompanying drawing forming a part thereof.

In the drawing, Fig. 1 is a front side view of a combination tool showing my design, and Fig. 2 is an edge view thereof.

I claim:

The ornamental design for a combination tool, substantially as shown.

OSCAR L. SWENSON.
